UNITED STATES PATENT OFFICE.

WILLIAM BAYLEY, OF SPRINGFIELD, OHIO.

APPARATUS FOR LAYING STREET AND ROAD PAVING MATERIAL.

1,258,299.

Specification of Letters Patent.

Patented Mar. 5, 1918

Application filed April 18, 1911. Serial No. 621,943.

To all whom it may concern:

Be it known that I, WILLIAM BAYLEY, citizen of the United States, residing at Springfield, in the county of Clark, State of Ohio, 5 have invented certain new and useful Improvements in Apparatus for Laying Street and Road Paving Material, of which the following is a specification, reference being had therein to the accompanying drawings.

10 This invention relates; to an apparatus for laying street and road paving material, such as cement mixed with broken stone, or similar material, to surface this material with asphalt or anything similar, to surface 15 old paved street with asphalt, or old macadam roads with cement or asphalt, by a method of rolling to make more perfect work, also, to effect a great saving of labor, and consequently to lower the cost of such 20 work, by a process of laying the sand and stone along the road or street, in the proper proportions, so that the apparatus can take its supply from the street or road, as it advances.

25 Heretofore it has been the practice, after a street or roadway has been graded, to make piles of sand in supposedly convenient places, also to make piles of stone in supposedly convenient places, keeping each 30 kind of material separate and distinct, and from which piles they are wheeled to a cement mixer, it must be delivered to a mixer box in the required quantities, namely, so many barrows of sand, then so many bar- 35 rows of stone, which are dumped into the mixer box, along with the proper proportions of cement. The count must always be kept. It is then elevated into the mixer, mixed with water and delivered into the 40 wheelbarrow, on the other side of the mixer, from this point it is again wheeled to wherever it is required on the street or roadbed, where it is spread and rammed down by hand. In these operations most all of the 45 material is handled twice and some of it three times by hand labor, and sometimes the scope of these operations extends over a whole city block. This apparatus will handle the material but once and by machine 50 labor, it is also capable of great speed.

Heretofore in surfacing a cement covered road or street, it has been the practice to dump wagon loads of mixed material (asphalt mixed with sand) upon the street, in 55 a hot condition, spread it with shovels and

rakes, as evenly as it is possible by hand, then roll it down with small road rollers, in order to get it compressed and well rolled on to and cemented to the sub-bed, but it is absolutely impossible to roll thus, every 60 square foot to the same amount of compression. This apparatus spreads the material evenly, keeps it warm, irons it down while warm, then rolls it to an even surface, by cross rolling, which continually rolls down 65 the whole surface, every square foot getting the same amount of rolling, and without crowding it out onto the sides of the road.

The preferred manner of placing the material in the street or road in front of my 70 apparatus, is to place it in a long pile, or a number of long piles, along the roadway, the number being determined by the width of the roadway, and the form of gathering up and elevating mechanism used. And it 75 can even be distributed over the whole roadway within a foot or two of the edges, placing the sand below with the stone above, placing the material in the required proportions, namely, one part sand to two parts stone, or 80 two parts sand to three parts stone, as may be desired. The object of placing the sand below is to have the gathering up mechanism work into the sand, and under the stone, and in this way doing cleaner and easier work. 85

The preferred form of my apparatus comprises a general frame, which is adapted to travel over the road-bed which is to be paved, and contains means for gathering up the material from the street or roadway, in 90 the nature of conveying screws, or shovels; means for elevating the material and delivering it to the mixers, in the shape of elevating buckets and hoppers; means for disposing of excess material, in the shape of 95 troughs and slides; means for mixing the material, in the shape of mixers; means for distributing the material across the road-bed and beating it down, in the shape of an elongated partly bottomless slot, filled with 100 sections of spiral bars, or broken screws, which are elevated to a little over the vertical position and then allowed to drop ahead by gravity, striking a blow against the material, settling the heavier pieces, bringing the 105 water to the top and at the same time moving it along each way from the mixer, to get an even depth in the slot; means to advance the apparatus, in the shape of carrying wheels, with levers and pawls; means to 110

smooth down and strike off the material, and other means to roll down the material at the rear of the apparatus, in the shape of rollers traveling across the roadway and at the same time trailing as much as is necessary, to suit the forward movement of the apparatus, which can either be intermittent or constant, according to the way it is geared; means to communicate to the cross rollers at the rear a motion like that in the piston of an engine, which gradually comes to a stop at each end, in the shape of a crank, communicating motion to a cable by elongation of its movement; means to lift one caster roller before it reaches the side of the paving-bed and lower another one beyond the edge of the paving-bed, so as to prevent wrinkling, in the shape of levers to throw the slide that carries the caster rollers over the center of its motion. If only one roller were used instead of the double caster, it would have to be lifted from the surface of the paving-bed before reaching the edge and turned around, it would be practicable, but more difficult, therefore, I have used the double caster rollers.

The apparatus is self-contained, in the sense, that it carries its own motor for operating the several parts, and for advancing it as the work progresses. It is controlled by an operator, who sits on a seat within view of the several operations going on and having the main clutch levers within reach.

My invention comprehends also such modification as would include the enumerated means or features with others, or with necessary adjuncts, as well as an apparatus having some or less than all of these features, as I consider myself to be the first to devise an apparatus, that will make possible a mechanical process, by which the crude material in front of a paving apparatus can be gathered up from the paving-bed, without the intervention of human labor; or make possible a mechanical method for rolling a paving-bed crosswise to prevent wrinkling by the material pushing ahead of the roller and crowding over on the edges of the paving-bed, it also rolls every square inch of the bed exactly the same number of times making it perfectly uniform in density and even in contour.

In the drawings Figure 0 is a partly sectional side view on the line (A A on Fig. 8) it shows the process material on the bed in front. Fig. 1 is a detached view of the hopper and scoop, just after it has been unlatched. Fig. 2 is a view of a modification of the end of the hopper, as it is used when the mixer is removed, when laying sheet asphalt. Fig. 3 is an outside view of the side of the apparatus. Figs. 4, 5, 6, are side, front and end views of the crank used to communicate forward movement to the apparatus. Fig. 7 is a section of a rein-

forced cement road, showing the reinforcing metal in the finished work. Fig. 8 is a plan view of the apparatus, with the tracks at the side of the road or street, showing the hopper and scoop elevated, showing the process material on the paving-bed in front. Fig. 9 is a front view of the end of the apparatus with the wire reel empty. Fig. 10 is a back view of the apparatus, and a section of a reinforced cement road with surface of asphalt. Figs. 11 and 12 are views of the washer on top of the caster trunnion, Figs. 13 and 14 are side views and plan of the slide carrying the caster rollers. Figs. 15 and 16 are side and end views of the trolley carriage, that carries the slide for the caster rollers. Figs. 17 and 18 are side and back views of the pulling and reversing levers, that communicate motion to the caster roller trolley. Fig. 19 is a side view of a three roller caster, showing each roller doing its part of the work. Fig. 20 is a side view, in section, of the apparatus adapted to laying and reinforcing sheet asphalt, shown with the caster roller coming toward you, and with the conveyer broken screws modified. It also shows a reinforced cement road with the surface of reinforced asphalt being laid on it. Fig. 21 is a side view of a modified device, for gathering in and elevating the material for the roadway, it shows a section of the process material in front. Fig. 22 is a front view of the same device. Fig. 23 is a plan view of the front of the apparatus, having a number of the devices shown in Figs. 21 and 22, four mixers and elevating devices, operating in two double units, it shows plainly a plan of the process material on the paving-bed in front of the apparatus. The arrows refer to the directions in which the apparatus, or separate parts are moving or about to start to move.

The numeral 1 designates a road-bed, graded and prepared to receive a layer of cement 2, which may or may not be given a surface coat 2'. In front of the apparatus, over the road-bed 1, an elongated pile of sand 1' and stone 1" has been placed, the stone on top of the sand, and both in the requisite quantity for the work to be done. At either side of the road-bed I place rails 3, held by blocks 4, these rails are secured to the blocks, and laid on a previously prepared cement gutter 4', or on a timber, which is intended to hold the cement on the side until it sets. The apparatus is supported by wheels, forward wheels 5, and rear wheels 6, which travel on these rails, the front wheels run on spindles 7, secured to bracket 8, the rear wheels run on spindles 9, secured to bracket 10.

The frame is composed of structural shapes, cross channels 11, 12, 13, 14, 15, 16, side channel 17, secured strongly together, 130

it is preferably made of metal but could be of wood, or wood and metal, the channels 13, 14, 15, 16 are further connected by plates 18, 19, 20, these plates also carry bearings 5 for the several shafts, lugs for the clutches and for various other uses.

At the forward end of plates 18 and 19, in bearings 21 is pivoted the plate 22, to which is secured a hopper 23—in Fig. 0 it is shown 10 in two positions, down and up, in Fig. 1 it is shown up also, but with the scoop unlatched. At the forward end of hopper 23, a shaft 24 is journaled across, on each end of the shaft a wheel 25 runs, these wheels carry the hopper 15 and follow the surface of the ground, so that the front lower edge of the hopper which is provided with teeth 26, cannot scrape below the surface of the ground, but just gather the loose material from the ground as the apparatus is advanced. Just 20 inside of the hopper 23, and secured to the shaft 24, is a scoop 27. In the down position of the hopper 23 on Fig. 0 this scoop is shown in full lines in its normal or rest position, with its scooped end drawn back within 25 the hopper, allowing the hopper to be advanced under the pile of material in front, and the latch 28, (which is secured to the link 29, by the links 30 and thrown forward by the spring 31,) thrown forward, and latched to the angle iron 32. Also in 30 the down position of the hopper 23, the scoop 27, is shown in dotted lines, drawn forward into the pile of material, and full of 35 material, this scoop is provided at its forward end, with teeth 33, to enable it to dig into the material easily. The scoop 27 thus not only serves to collect the material but also serves as a gate for the lower end of 40 the hopper or chute 23 to retain therein the collected material during the upward swinging movement of the hopper or chute. The hopper and scoop thus form a pivoted telescopic receiving chute, of 45 which the scoop forms a telescopic gate operating in an arcuate path. In the up position of the hopper, the scoop is still shown in the same position, as in the dotted lines below, but with the latch 28 drawn against the 50 stop 34, and the latch unhooked from the angle iron. When in this position, the scoop turns by the pull on the link 29, which is pivoted to an arm 35, the arm and the scoop both being secured rigidly to the shaft 24. 55 The hopper now drops forward and a little down until the hopper and the scoop occupy the position shown in Fig. 1 and it is also now ready to be lowered to its normal down position, shown in Fig. 0. But when 60 the hopper and wheels first touch the ground, the cable 36 will be taut, and the latch and link will occupy position D, shown in dotted lines. It will thus be seen that at the initial operation of the cable 36, the scoop 65 or telescopic gate is operated independent

of the receiving chute or hopper and by subsequent operation, the two said members are elevated in unison, the scoop or telescopic gate being released when the chute or hopper reaches a predetermined position. 70 In order to again fasten the latch, a bail 37, is pivoted to each side of the hopper, it is arranged to be thrown forward by a spring 38, on each side of the hopper, and as the cable slackens, it forces the latch and link forward 75 until the latch is again caught on the angle 32, and the cable becomes slack and the hopper and scoop are again in the normal position, ready to repeat their motion. Cable 36 is operated over a wheel 36' pivoted on the 80 pin 36" at the top of the derrick standards 36"". The combined hopper and scoop when it is lifted, delivers the material from the road-bed, into a suitable mixer 39 which receives motion from the shaft 53, through 85 the chain wheels 85, 86 and the chain 86'. The hopper while being lifted overturns a water box 40, by means of a rod 41. The material is thus mixed with water and with cement, which has previously been dumped 90 into the hopper, all passing into the mixer, and when it is properly mixed, the operator turns the spout 42, by means of a handle 43, and the material is dropped into a partly bottomless elongated slot 44, extending in 95 the apparatus clear across the roadway, where the material is operated upon by the beaters and conveyors 45. As the machine advances the smoothing bottom 44' passes over the material which has been operated on 100 in the elongated slot, it presses it down, and smooths it, and leaves it in a finished state, unless it is desired to roll it afterward, this process I will describe further on. Beaters 45 are rotated by the dogs 46, these dogs are 105 secured to the shaft 47 and allow a certain amount of free motion to the beaters, which lets them drop ahead. The shaft gets its rotary motion from the worm wheel 48, secured to it, and operated by a worm 49, 110 through the shaft 50, and bevel gears 51 and 52. Wheel 52 is secured to shaft 53, which receives motion from the gear 54, through a clutch 55, thrown in by a lever 56. Gear 54 is in turn driven by the double intermediate 115 gear 57, and the pinion 58, on the motor 59. All of the separate movements are capable of being disengaged by clutches, and the important clutches are all within reach of the operator, who sits on the seat 59' which is 120 supported by the spring 59". Shaft 53 at its rear end has a worm 60, which drives a worm wheel 61, the worm wheel 61 is secured to shaft 62, which runs in bearings on the plates 18, 19, 125 20, channels 17 and bracket 63. Just back of the center of the mixer, it carries a drum 64, this drum 64 winds up the cable 36, when the friction clutch 65 is thrown in by the handle 66. When wound up it is held by a brake 130

band 67 one end of which is pivoted to the pin 68, on the bracket 69, the other end is pivoted to the lower end of the lever 70 which is also pivoted on the bracket 69, this 5 brake also lets out the cable as desired and lowers the hopper 23.

Mounted low on the front of the apparatus, is a long reel 71', upon which prepared wire 71 is wound, this wire consists of 10 long strands wound around the reel at intervals, and connected crosswise and in line with the axis of the reel by wires 72, making a mesh of any desired size. It can be made of any desired gage, to suit the work. I do 15 not restrict myself to this particular kind of prepared wire, the apparatus can use any style of commercial woven wire, or rope, or cord net, or can use numerous rolls of plain single wires, to lie in lines along the road-way, and the cross wires can be put on as 20 the work progresses. This wire passes under the bottom or gage block 73, which extends down to within the required distance from the earth. The wire being drawn taut across the 25 gage block, is held up over the paving-bed to a point where it is desired that it should be embedded into the cement or other substances. At the commencement of this work, all of the wires 71 are fastened to stakes, and the 30 wire is kept taut by a friction brake block 74, which is secured to lever 75, which is pivoted to bracket 76, and held down by the weight 77, onto the brake wheel 78, the brake wheel being secured to the reel.

35 The foregoing description deals with the parts of my invention more particularly adapted to cement work on narrow road-ways. I will now refer to a modification of the gathering up and elevating mechanism for taking the material from the road-way, which is better adapted to wide road-ways, and more speedy work.

40 Sand and broken stone have been placed on the road-bed 1, in the same manner as 45 has been described.

Referring to Fig. 23 shaft 53 is extended at its forward end and has secured to it a gear 79, which drives a gear 80, which is secured to the shaft 81, this shaft extends 50 across the front of the apparatus and is carried by bearings in brackets 82. Secured to the shaft are also gears 83, that communicate motion to the mixers 39, through the shafts 84, and the sprocket 85 and 86. 55 Also secured to shaft 81 are sprockets 87, which communicate motion to the elevator shafts 88, through the chains 89, to the sprockets 90.

60 Trunnions on the ends of the bearings on brackets 82, carry links 91 and links 92, links 91 have bearings in their top ends, in which shafts 88 run. Shafts 88 have suspended on their centers, links 92, which extend down and suspend at their lower ends 65 shafts 94. Shafts 94 also run in bearings

carried by links 92'. Links 92' are pivoted on shafts 95, these shafts are secured to links 92. Links 92 have extensions 92'', on the ends of which are pivoted pins 92''' with holes through them through which pass bolts 70 92''', these bolts are secured to links 92, by pins 92'''', the bolts are secured to pins 92'' by nuts on each side. It will be seen that this arrangement of parts, secures links 92, and 92'' rigidly together and at the same 75 time makes an adjustment at these points to be used in case of higher or lower levels of the sub-road-way 1. It will also be seen that when all of these links 91, 92, 92', 93 are connected up, they form rigid structures, 80 but are free to turn on the trunnions on brackets 82. These structures are carried on the wheels 96, which run on the ends of the shafts 95 and control the depth to which the screws 97, and buckets 98 shall dig. 85 Buckets 98 are connected by links 99, forming chains, which are driven by chain sprockets 100, and in this way elevate the material, and communicate motion to the shafts 94, by the chain sprockets 101, which are secured to the shafts 94.

Shaft 94 extends on each side of the elevator chain and buckets, and carries right and left screws 97, which, when rotating convey the material to the center, and with- 95 in reach of the elevator buckets 98, by which it is elevated and dropped into the hopper 102. When the hopper 102 is full, it is emptied into the mixer 39, by means of a valve 103. This valve is on a shaft 104. The 100 shaft is operated by a lever 105, the lever also holds the valve open or shut, by means of a hand latch 106, and the segment 107, which is notched to receive the latch, and this lever also turns the water box 40, by means of a 105 link 41, at the same time that it is opening the valve 103. The water box 40 is supported by standards 108, and 108' on the hopper 102. The opening of the valve 103, delivers the material into the mixers 39, where the 110 same operation is taken up as has been described. To meet the emergency of too much material being elevated to supply the mixers 39, I have added to the side of the hopper 102, a spout 109, through which excess ma- 115 terial may be allowed to pass and be deposited on the side of the road, by lifting slide 110. Connected with links 92 and to back up the work of the conveyer screws 97, and the buckets 98 is a shield 111.

I will now refer to parts of the apparatus, that have not been referred to up to the present time, and which apply principally to the use of the apparatus, in doing sheet asphalt or similar paving work. In doing 125 such work, the street or road, is either an old paved street, an old macadam road, or a new paved street or road, that has already had the cement laid down on the roadway, the sheet asphalt paving in each case being a 130

surfacing. The prepared mixture is hauled to the site, from a plant where it has been mixed (which is generally placed near a railroad) and the material is delivered on 5 the site hot, and dumped in front of the elevator. There is no necessity of a mixer on the machine, so the mixer 39 is removed, and if hopper 23 is used, it is extended as shown in Fig. 2, by the end 23', so that it 10 delivers the material direct into the slot 44, or if the hopper 102 is used, a similar extension would be made to it. If the asphalt is to be reinforced with wire or cord, the 15 process is similar to that used in the cement work, which has been described, although the wire would be finer both in gage and mesh. After the asphalt has been dropped into the slot 44, it is distributed by the 20 broken conveyer screws 45' and a special smoothing bottom 44'', smooths it down to a point high enough above the finished grade to allow for the rolling down which is to follow.

At the rear of the apparatus two channel 25 irons 11 and 12 extend across, they are secured to the side channel irons 17 at each end, and are held rigidly together by blocks 112 and bolts 113, and adjustable blocks 114, with their bolts 115 and 116; thus making 30 a solid beam. There is mounted on the lower flanges of this beam, a trolley 117. It is carried by roller 118 above, and is kept from lifting by the roller 119 below. This 35 trolley travels back and forth on this beam, and is limited in its movement by the stops 120. On the lower edge of this trolley there is a curved slide 121 extending outside on each side, and arranged to work on this slide is another slide 122, the slide 122 has notches 122', into which the rollers 123, of the lever 40 124 work, the lever 124 is pivoted to the trolley 117, by the pin 124', in the hole 124''. It will be seen that by moving the lever 124 back and forth, when so assembled, the slide 122 will work back and forth on the trolley 45 117, or reverse. Mounted in the lever 124 is a pin 124''' with a hole in its center cross-wise, in which to fasten the end of the cable 125.

It will be seen that when the cable 50 125 pulls the lever 124 in the direction of the arrow, the slide 122 will be held back to the position shown in Fig. 10, then by continued pulling of the cable, the whole trolley will be pulled toward the opposite end 55 of the beams, until the roller 124''' in the top of the lever, comes in contact with the block 114, then by continued pulling of the cable, the slide 122 will be reversed, and put into the position to return to the other end 60 of the beam.

In the center of the slide 122 a hole 122'' is provided, concentric with this center is a ball groove 122''' on both the top and bottom of the slide, this groove is for balls to 65 travel in. Into the hole 122'' from below,

is inserted the stem 126' of the caster 126, the top of the caster has a groove similar to 122'', so that balls work between these surfaces. The part of the stem 126' that extends through and beyond the slide 122 is 70 squared and on it a washer 127 is fitted, and is held on by a nut 127'. This washer has also a groove corresponding to 122'', which provides for balls to work between these surfaces. The object of the ball bearing is 75 to make a very sensitive working joint. At each end of the caster 126 on shaft 126'' is mounted a roller 128, and on caster 126 there are also bolted scrapers 129.

It will be seen that when the slide 122 80 has been reversed, it will stand as shown in Fig. 10, with the extreme outside roller on the ground and ready to roll down as much of the asphalt, as has been presented by the forward movement of the apparatus, 85 and to reroll all that it will cover for the rest of its width, and it will continue to do this in its movement across the road-way, until the roller 124''' strikes the block 114, and the reverse movement begins. The roller 90 128 will at this time have reached the position E, shown in dotted lines, when it will be lifted from the surface gradually as the reversing process progresses, and the other roller on the other end of the caster will be 95 lowered. In the reverse movement the other roller will leave the surface at the point E'.

It will be observed that by this method of 100 rolling the material is always kept in the center of the road-way and no wrinkling can occur at the side. In Fig. 19 is shown a modification of the caster frame 126 having three rollers mounted therein, this is to show that I do not confine myself to two 105 rollers but can use three or more.

In order to give a reciprocating movement to the trolley 117, and in order to prevent shock at each end of its movement, but to gradually stop and start it, the apparatus has been arranged to give motion to the cable 125, from the crank 130 which is secured to a shaft 131, working in the bracket 132. On the other end of the shaft 132, a gear 133 is secured, and meshes into a gear 134, which is loose on the shaft 62, and is driven by a clutch 135, thrown in by a handle 136. The crank 130 gives a rocking motion to a segment 137, by means of the pins 138 and 139, and the rod 140. This segment rocks on the pin 141, held by the bracket 142, and gives motion to the shaft 120 143, back and forth, by the pinion 144. The shaft 143 is carried by the brackets 145 and 146. Secured to the shaft 143 is a concave faced drum 147, around which the cable 125 is wound, and as the drum rotates back and forth, the cable is pulled 125 back and forth just sufficient to give the required motion to the trolley 117, back and forth.

Trolley 117 is provided with stop screws 130

117' which can be set to limit the movement of the lever 124, in the same way blocks 114 can be adjusted by the slots in the blocks, and in the beams.

5 In working asphalt it is necessary to keep it warm, so that it will not freeze up in the apparatus, to accomplish this the smoothing bottom 44" is hollow and steam tight, also bottom 73 is the same way. These form 10 jackets and there are also provided other jackets 148 and 149. 148 is connected to 44" by holes 150, and 149 is connected to 73" by holes 151. The apparatus carries a small boiler 152, shown on Fig. 8. It is mounted 15 on a plate 152', it is connected by steam pipe 153, to the bottom 44". Steam or hot water circulates through the jacket 44" and 148, to the steam pipe 154, at the other end of the apparatus. It then passes over into the 20 jackets 73' and 149, and returns through them to the steam pipe 155, thence it goes to the boiler or out into the atmosphere. In this way the asphalt is kept hot, allowing the apparatus to work it freely, allowing the 25 smoothing bottom 42" to press it down into all the inequalities, of the cement, and to thoroughly embed the reinforcing wire or cord, also allowing rollers 128 to still further roll down, compress, and embed the 30 material, and leave a perfect and evenly treated roadway. The rollers 128 can be cooled with a spray of water.

The rollers 128 are attached to a caster, in order to allow them to trail freely, so that 35 it does not matter when the machine is advanced, there will be no pulling of the rollers endwise, otherwise, the two operations of rolling down the paving bed and advancing the apparatus could not be carried on together.

I will now refer to the moving of the apparatus, at each end of the shaft 62 on the outside of the apparatus, is secured a crank 156. These cranks have sliding pins 156' 45 which can be adjusted to and from the center of the crank, then by means of the rod 157, the cranks communicate motion to the rock arms 158, these rock arms work on the pins 9, and have a friction pawl 159, that works 50 into the grooved back wheels of the apparatus, so that they bind while moving the apparatus, forward, and are relieved when the arms are backing. Used in connection with these arms and pawls, are the holding pawls 55 160, to prevent any backing tendency, they pivot on the pins 161, and allow the apparatus to move forward freely, but will not let it back. It will be seen that by adjusting the pin 156', toward the center of the cranks 60 156, the motion of the machine can be made less and less in order to time the movement of the machine to the operations being performed by it. It will be seen that by grooving the back wheels it gives them a grip on

the track and gives the pawls a grip on the 65 wheels.

I will now refer to the mechanism for winding the wire on to the reel. Mounted loose on the end of the shaft 62, is a sprocket 162, inoperative until the clutch 163 is 70 thrown in by the handle 164, when it communicates motion to the reel 71', by means of a chain 165 chain wheels 166 and idler 167. The apparatus having been stopped by throwing over the pawls 159, the reel now 75 receives a backward or winding up motion, by which wire can be wound on it.

Referring now to the general operation of my apparatus, it will be seen and understood that, as the apparatus advances along 80 the paving-bed, it will supply or feed itself with the material from in front of it, which material will be elevated into the mixer, or delivered into the elongated partly bottomless slot, and is distributed across the width 85 of the roadway evenly, then as the apparatus advances, the smoothing bottom presses it down and smooths it. With some kinds of material at this stage the work is completed, and there is left behind a finished road, but 90 with such material as sheet asphalt the material is subjected to a process of cross rolling at the rear of the apparatus, the roller mechanism being light and working rapidly, with the weight of the apparatus above it, giving 95 it efficiency to compress the material being rolled. It will be seen and understood, that the work of this apparatus can be accomplished with a minimum amount of man labor and that it must necessarily be very 100 perfect, inasmuch as the forward movement of the machine is constant and regular, the rolling down of the material at the rear, must be constant and regular for at each time that the roller makes a pass across the roadway, the apparatus has advanced a regular distance, in this way, every inch of the roadway gets exactly the same treatment, which is the only way in which to make a perfect 105 road. It will also be seen and understood 110 that the apparatus can be used either to reinforce the paving material with wire, or not, to suit the case in hand, and when the process of reinforcing the paving material is used, the wire having been secured at the start will automatically be unwound from the reel, as the apparatus advances and will automatically be covered up, and well embedded into the paving material. This 115 method produces a road that will stand harder usage in cement, as well as in sheet asphalt and in asphalt. It prevents stretching and working into blisters.

Referring to the process of placing the material on the roadway piled in the convenient way, for the apparatus to take its supply, as it is advanced, it will be seen and understood that this process entirely elim- 125

inates the man labor, heretofore used in this part of the work, and is the means of saving the largest per cent. of the man labor in doing this kind of work.

5 This application in so far as it relates to sheet asphalt work is the application referred to in my application of April 5th, 1909.

Having thus fully described my invention, what I claim as new and desire to secure by

10 Letters Patent, is:—

1. In a paving apparatus, a bridge-like main frame, supportable at the sides of the paving bed and forwardly movable relatively to and over the paving-bed, a bottom 15 to gage off and smooth down mixed paving material on the surface of the paving-bed carried by said frame, means flexibly attached to and in front of said frame, to gather up, elevate and deliver to a mixer 20 carried by said frame, loose material that has been resting on the surface of the paving-bed, said means freely following the inequalities in the paving-bed, irrespectively of the vertical position of said frame, and 25 power means working irrespectively of the forward movement of the apparatus to distribute the material delivered from the mixer, across the width of the apparatus in front of the gaging off and smoothing down 30 bottom.

2. In an apparatus of the character described, a traveling main frame, a material receiving compartment thereon having an elongated material discharge orifice extending across the surface operated upon, means for automatically distributing the material throughout the extent of the discharge orifice, and material compressing means acting upon the discharged material.

40 3. In a paving apparatus, a bridge-like main frame supportable at the sides of the paving-bed and movable relatively to and over the paving-bed, means flexibly attached to and in front of said main frame to gather 45 up, elevate, and deliver, loose material from the surface of the paving-bed between two walls carried by said frame, which inclose a bottomless space extending across the width of the paving-bed, where the material 50 is distributed, said means freely following the inequalities in the paving-bed, irrespectively of the vertical position of said main frame, means carried by said frame to heat said walls, a smoothing bottom at the lower

55 end of the rear wall, means carried by said frame to heat said bottom, and means to distribute the material across the width of the apparatus between said heated walls and in front of said heated smoothing bottom.

60 4. In a paving apparatus, a bridge-like main frame, supportable at the sides of the paving-bed and forwardly movable relatively to and over the paving-bed, a gaging and smoothing bottom, means for heating

65 said gaging and smoothing bottom, means for distributing the material across the width of the apparatus, carried by said frame, means carried by said frame to heat paving material as it is distributed across the 70 width of the apparatus, and the gaging and smoothing bottom following said material heating means, means to press down or iron said material as the apparatus is moved forward.

5. In a paving apparatus, a bridge-like 75 main frame, supportable at the sides of the paving-bed and movable relatively to and along the paving-bed, a gaging, smoothing and compressing bottom carried by said frame, means for heating such transverse 80 smoothing and compressing bottom extending across the paving-bed, means for heating said bottom, a device for rolling down the paving material carried by said frame, means to work said device crosswise of the 85 paving-bed, means for distributing material across the paving-bed between heated walls, the material distributing means preceding said gaging smoothing and compressing bottom, and compacting means following the 90 said gaging, smoothing and compressing bottom.

6. In a paving apparatus, a bridge-like 95 main frame supportable at the sides of the paving-bed and movable relatively to and along the paving-bed, a device connected to said frame for gathering up material from the surface of the paving-bed, said device resting on the surface of the paving-bed on its own supports, means to elevate the material gathered up by said device carried by said frame, a mixer to receive material from said elevator carried by said frame, a spout to receive material from said elevator and drop it beyond the side of the paving-bed, carried by said frame, and other means to direct the elevated material either entirely or partly into either the mixer or the spout.

7. In a paving apparatus, a main frame 100 supportable and movable relatively to the paving-bed, a self-supporting hopper shaped device, resting on the paving-bed, and floatingly hinged to and in front of said frame, means carried in said hopper to scoop up loose material from the surface of the paving-bed, said means holding said material, and means to elevate, empty and lower said hopper.

8. In a paving apparatus, a main frame 105 supportable and movable relatively to the paving-bed, a hopper shaped gathering up and elevating device hinged at its back end to said frame, a shaft secured across the front end of said device, a wheel mounted on each end of said shaft and resting on the paving-bed, a concentric shaped scoop mounted on each side of the center of said shaft, a latch arm mounted on the center of

said shaft, a hoisting cable attached to said latch arm, forwardly projecting arms extending from said concentric scoop, a cross bar between the ends of the forwardly projecting arms, to which said latch arm latches, and power means to pull or release said cable.

9. In a paving apparatus, a main frame supportable and movable relatively to the 10 paving-bed, a gathering up and elevating device, means to raise and lower said device, the back end of said device flexibly connected to said frame, the front end of said device carried on supports which follow the inequalities of the paving-bed, and power means to operate the device.

10. In a paving apparatus, a main frame supportable and movable relatively to the paving-bed, a gathering up and gathering 20 in device comprising an oscillatory chute inclined downwardly and forwardly when in gathering or receiving position and movable to an upwardly and forwardly inclined position for discharging the gathered material, said device being flexibly connected with said main frame for oscillatory movement about an axis fixed in relation with the main frame, the front end of said device carried on supports which follow the inequalities of the paving-bed, irrespectively 30 of the vertical position of said frame.

11. In a paving apparatus, a main frame, supportable over the paving-bed, walls carried by said frame and extending across the 35 paving-bed, which inclose a bottomless space in which to distribute mixed material, means carried by said frame to deliver mixed material upon the surface of the paving-bed between said walls, a revoluble 40 shaft carried by said frame and mounted along between said walls, on which conveyer beaters are arranged, said beaters taking said mixed material from the points of delivery, and distributing it across the surface 45 of the paving-bed, until it is an even depth, and power means to actuate said shaft.

12. In a paving apparatus, a main frame, supportable over a paving-bed, walls carried by said frame, and extending over and 50 across the paving-bed, which inclose a bottomless space, means carried by said frame to deliver mixed material upon the surface of the paving-bed and distribute it evenly across the surface of the paving-bed along 55 said space, said walls being made hollow and steam tight, to allow steam or hot water to be circulated through them, and means to furnish hot water and steam and to circulate it through said walls.

60 13. In a paving apparatus, a main frame supportable and forwardly movable relatively to the paving-bed, two walls carried by said frame, and extending over and across the paving-bed, which inclose a bottomless space, means carried by said frame

to distribute mixed paving material evenly across said space and the rear wall of said two walls having a hollow steam tight gagging and smoothing bottom secured to it, means to heat water and generate steam and 70 to circulate the same through said bottom carried by said frame, and means to move the apparatus forward and bring said gagging and smoothing bottom into action.

14. In a paving apparatus, a main frame 75 supportable and movable relatively to the paving-bed and rear end of said frame forming a transverse beam, which spans the paving-bed, a rolling device sliding on said beam, the under side of said beam conforming to the transverse line of the paving-bed, and the under side of said beam being high enough above the paving-bed, to admit of means for rolling down the paving-bed, being slidably mounted thereto.

15. In a paving apparatus, a main frame, supportable and movable relatively to the paving-bed, a transverse beam carried by said main frame, spanning the paving-bed, the under side of said beam conforming to 90 the transverse line of the paving-bed, and a device consisting of a plate slidably mounted on the under side of said beam, a concave slide on the under side of said plate, a plate with a curved top mounted in the 95 concave slide and having a limited rocking motion in the direction of the center line of the beam, said curved topped plate having a trunnion hole in its center, in which is centered a double ended caster, with a roller or 100 rollers in each end.

16. In a paving apparatus, a main frame, supportable and movable relatively to the paving-bed, a transverse beam carried by 105 said main frame, spanning the paving-bed, with its under side conforming to the desired line of the paving-bed, a device consisting of a plate slidably mounted on the under side of said beam with a concave slide on its under side in which another plate is 110 mounted and has a limited rocking motion in the direction of the travel of the device, said rocking motioned plate having a double ended roller caster trunnioned to its under side, the device being moved back and forth 115 from near one end to near the other end of the beam, and means to cause said rocking motioned plate and its caster rollers to be moved forward just at the time that the device reverses at the end of its movement, 120 whereby the back roller is raised from off the paving-bed, and the front roller lowered to the outside of the paving-bed.

17. In a paving apparatus, a main frame, supportable and movable relatively to the 125 paving-bed, a transverse beam carried by said main frame, spanning the paving-bed, said beam being double on its lower side and allowing a slot in its center, the under side of said beam conforming to the desired 130

transverse line of the paving-bed, a device 5
slidably mounted on the under side of said beam, consisting of a top plate with a concave slide on its under side, in which a rocking plate having a double ended roller caster trunnioned under it rocks, said top plate having a lever mounted on a pin centrally in each end, the tops of said levers extending up into the slot, in the beam, and having 10
a cable connected to them part way up, the lower ends of said levers extending down into notches in said rocking plate, and means to pull the cables alternately until the extreme top ends of the levers strike 15
stops and reverse the rocking plate.

18. In a paving apparatus, a bridge-like main frame, supportable at the sides and movable relatively to the paving-bed, and carrying means to smooth off and roll down 20
a paving-bed, a smoothing bottom supported by said frame, means to heat said bottom, and the rolling down device mounted to travel on said frame back and forth across the paving-bed, and behind said heated smoothing bottom.

19. In a paving apparatus, a main frame, supportable and movable relatively to the paving-bed, a transverse beam carried by 25
said main frame, spanning the paving-bed, with its under side conforming to the desired line of paving-bed, a device for rolling down the surface of the paving-bed, slidably mounted on the under side of the said beam and reciprocated back and forth 30
on said beam across the width of the paving-bed by motion received from a crank, a shaft with a crank on its end mounted on said frame and rotated by the motive power 35
of the apparatus, and means between said 40
crank and said reciprocating rolling device, to increase the movement received from said crank, by gearing up, to a degree where the movement is equal to the movement of said reciprocating rolling device to which 45
the movement is communicated.

20. In a paving apparatus, a main frame supported on the sides of the paving-bed, and movable relatively to and over the paving-bed, a transverse beam spanning the 50
paving-bed, carried by said frame, with its under side conforming to the desired transverse form of the paving-bed, a device for rolling down the surface of the paving-bed slidably mounted on the under side of said 55
beam, reciprocating back and forth on said beam across the width of the paving-bed, while rolling down the surface of the paving-bed to conform to the line established by the rails on which the side supports of 60
said frame travel, and said device having a caster roller mounted under it which is adapted to trail after said device, while also trailing after a forward movement of the apparatus.

21. In a paving apparatus, a main frame,

supported on the sides of the paving-bed and movable relatively to and over the paving-bed, a transverse beam spanning the paving-bed, carried by said frame, with its under side conforming to the desired 70
transverse form of the paving-bed, a device for rolling down the surface of the paving-bed, slidably mounted on the under side of said beam, reciprocating back and forth on said beam across the width of the paving- 75
bed, while rolling down the surface of the paving-bed to conform to the line established by the rails on which the side supports of said frame travel, said device having a caster roller mounted under it, which 80
is adapted to trail after said device while also trailing after a forward movement of the apparatus, and power means to operate the rolling device and the forward movement of the apparatus singly or jointly. 85

22. In a paving apparatus, supported on the sides of the paving-bed, and movable relatively to and over the paving-bed, a device for rolling down the surface of the paving-bed slidably mounted on the under 90
side of said frame, reciprocating back and forth transversely across the width of the paving-bed, in a line conforming to the desired transverse form of the paving-bed, a 95
rocking slide mounted under said device, a roller connected to and under each end of the rocking slide, the rocking slide so operated that considering the direction of movement of the device, the back roller is always down and the front roller always up, and 100
means to rock the slide forward as it has been traveling when the device reverses at each end of its movement, whereby the back roller is lifted before it has traveled entirely 105
across the paving-bed and the front roller is lowered on the extreme side edge of the paving-bed.

23. In a paving apparatus, a main frame, supportable and movable relatively to the paving-bed, two walls carried by said frame 110
extending across the paving-bed, between which mixed paving material is distributed along, a shaft located centrally between said walls, and rotating therein to revolve conveying beaters mounted thereon, and said 115
beaters extending radially from said shaft and terminating in a spiral bar, to drop into the material resting on the paving-bed as the shaft revolves, whereby the material is beaten and distributed. 120

24. In a paving apparatus, a main frame, supportable and movable relatively to the paving-bed, a shaft mounted centrally along a transverse bottomless slot and rotating therein, to revolve conveying beaters mounted loosely thereon, two beater arms extending radially from hubs around said shaft and terminating in a spiral connecting bar, notched ended dogs permanently keyed to 125
said shaft and located between the two 130

117' which can be set to limit the movement of the lever 124, in the same way blocks 114 can be adjusted by the slots in the blocks, and in the beams.

5 In working asphalt it is necessary to keep it warm, so that it will not freeze up in the apparatus, to accomplish this the smoothing bottom 44" is hollow and steam tight, also bottom 73 is the same way. These form 10 jackets and there are also provided other jackets 148 and 149. 148 is connected to 44" by holes 150, and 149 is connected to 73" by holes 151. The apparatus carries a small boiler 152, shown on Fig. 8. It is mounted 15 on a plate 152', it is connected by steam pipe 153, to the bottom 44". Steam or hot water circulates through the jacket 44" and 148, to the steam pipe 154, at the other end of the apparatus. It then passes over into the 20 jackets 73' and 149, and returns through them to the steam pipe 155, thence it goes to the boiler or out into the atmosphere. In this way the asphalt is kept hot, allowing the apparatus to work it freely, allowing the 25 smoothing bottom 42" to press it down into all the inequalities, of the cement, and to thoroughly embed the reinforcing wire or cord, also allowing rollers 128 to still further roll down, compress, and embed the 30 material, and leave a perfect and evenly treated roadway. The rollers 128 can be cooled with a spray of water.

The rollers 128 are attached to a caster, in order to allow them to trail freely, so that 35 it does not matter when the machine is advanced, there will be no pulling of the rollers endwise, otherwise, the two operations of rolling down the paving bed and advancing the apparatus could not be carried on together.

I will now refer to the moving of the apparatus, at each end of the shaft 62 on the outside of the apparatus, is secured a crank 156. These cranks have sliding pins 156' 45 which can be adjusted to and from the center of the crank, then by means of the rod 157, the cranks communicate motion to the rock arms 158, these rock arms work on the pins 9, and have a friction pawl 159, that works 50 into the grooved back wheels of the apparatus, so that they bind while moving the apparatus, forward, and are relieved when the arms are backing. Used in connection with these arms and pawls, are the holding pawls 55 160, to prevent any backing tendency, they pivot on the pins 161, and allow the apparatus to move forward freely, but will not let it back. It will be seen that by adjusting the pin 156', toward the center of the cranks 60 156, the motion of the machine can be made less and less in order to time the movement of the machine to the operations being performed by it. It will be seen that by grooving the back wheels it gives them a grip on

the track and gives the pawls a grip on the 65 wheels.

I will now refer to the mechanism for winding the wire on to the reel. Mounted loose on the end of the shaft 62, is a sprocket 162, inoperative until the clutch 163 is 70 thrown in by the handle 164, when it communicates motion to the reel 71', by means of a chain 165 chain wheels 166 and idler 167. The apparatus having been stopped by throwing over the pawls 159, the reel now 75 receives a backward or winding up motion, by which wire can be wound on it.

Referring now to the general operation of my apparatus, it will be seen and understood that, as the apparatus advances along 80 the paving-bed, it will supply or feed itself with the material from in front of it, which material will be elevated into the mixer, or delivered into the elongated partly bottomless slot, and is distributed across the width 85 of the roadway evenly, then as the apparatus advances, the smoothing bottom presses it down and smooths it. With some kinds of material at this stage the work is completed, and there is left behind a finished road, but 90 with such material as sheet asphalt the material is subjected to a process of cross rolling at the rear of the apparatus, the roller mechanism being light and working rapidly, with the weight of the apparatus above it, giving 95 it efficiency to compress the material being rolled. It will be seen and understood, that the work of this apparatus can be accomplished with a minimum amount of man labor and that it must necessarily be very 100 perfect, inasmuch as the forward movement of the machine is constant and regular, the rolling down of the material at the rear, must be constant and regular for at each time that the roller makes a pass across the roadway, the apparatus has advanced a regular distance, in this way, every inch of the roadway gets exactly the same treatment, which is the only way in which to make a perfect 105 road. It will also be seen and understood 110 that the apparatus can be used either to reinforce the paving material with wire, or not, to suit the case in hand, and when the process of reinforcing the paving material is used, the wire having been secured at the start will automatically be unwound from the reel, as the apparatus advances and will automatically be covered up, and well embedded into the paving material. This 115 method produces a road that will stand harder usage in cement, as well as in sheet asphalt and in asphalt. It prevents stretching and working into blisters.

Referring to the process of placing the material on the roadway piled in the convenient way, for the apparatus to take its supply, as it is advanced, it will be seen and understood that this process entirely elim- 125

- making material, the road making material being discharged intermediate the parallel walls, and means to distribute the material transversely in relation with the road bed.
- 5 38. In a machine of the character described, a traveling main frame movable in line with the road bed, two parallel walls carried by the main frame, spaced apart and arranged transversely in relation with the main frame.
- 10 road bed, thereby forming a bottomless slot intermediate the walls, a conveyer located intermediate the walls adapted to distribute road making material discharged into the bottomless slot intermediate the walls.
- 15 39. In a machine of the character described, a traveling main frame movable in line with the road bed, a gage member carried by the main frame and arranged transversely in relation with the road bed and the lower edge of which is elevated above the road bed a distance substantially equal to the desired depth of the covering of road making material, and a transversely disposed conveyer located in advance of the
- 20 25 gage member adapted to distribute road making material laterally across the road bed.
40. In a machine of the character described, a traveling main frame movable in line with the road bed, a material supply compartment located on the main frame, and a mutilated screw conveyer carried by the main frame and arranged transversely in relation with the road bed, said mutilated screw being adapted to distribute road making material laterally across the road bed.
- 45 41. In a machine of the character described, a traveling main frame movable in line with the road bed, material feeding means carried thereby, a plurality of spiral conveyer sections arranged in axial alignment transversely in relation with the road bed, each conveyer section being capable of movement about the common axis independent of the remaining sections.
- 50 42. In an apparatus of the character described, a traveling main frame, a presser device adapted to engage the road surface operated upon and movable in a direction transverse to the path of travel of the machine, means for automatically engaging the presser device with the road surface adjacent to one edge thereof, and means for lifting the presser device before it reaches the opposite edge of the roadway in its transverse path of travel.
- 55 43. In a machine of the character described, a traveling main frame, means carried thereby for collecting road making material placed in advance of the main frame in the path of travel thereof, a mixer upon the main frame into which the collected material is discharged, means for distributing the material laterally across the path of travel of the main frame, means for gaging the depth of the distributed material, and means for compacting the gaged bed of material in unison with the advance of the main frame.
- 60 44. In an apparatus of the character described, a traveling main frame, an oscillatory carriage mounted on said main frame for reciprocatory movement, independent of its oscillation, in a direction transverse to the path of travel of the apparatus, separate presser devices carried by said carriage, and means to oscillate the carriage at the limits of its reciprocatory movement whereby the presser devices will be alternately engaged with the road surface operated upon.
- 65 45. In an apparatus of the character described, a traveling main frame, and pressure applying means carried thereby adapted to engage the road way and movable alternately in opposite directions transversely to the path of travel of the machine, and means controlling the operation of said pressure applying means whereby the presser means will begin its operation at a point beyond the termination of the preceding stroke.
- 70 46. In an apparatus of the character described, a traveling main frame, reciprocatory pressure applying means moving in directions transverse to the path of travel of the apparatus, and means controlling the operation of the pressure applying means whereby succeeding strokes of said means will begin at opposite edges of the road bed and will terminate before reaching the opposite edge of the road bed, substantially as specified.
- 75 47. In an apparatus of the character described, a traveling main frame, two presser devices carried thereby and movable transversely across the path of travel of the apparatus, and means for alternately engaging the presser devices with the roadway, and means for disengaging each presser device from the roadway at the limit of its path of travel.
- 80 48. In an apparatus of the character described, a traveling main frame, means carried by the main frame for collecting from the road bed in advance of the apparatus road surfacing materials, a material mixer carried upon the main frame, a distributor adapted to distribute the mixed material laterally across the path of travel of the apparatus, tamping means for compacting said deposit, a gage member carried by the main frame adapted to stroke off the excess of material thereby forming the deposit into a layer of even surface, and surfacing means operating transversely to the path of travel of the main frame.
- 85 49. In an apparatus of the character described, means for compacting plastic material deposited upon the road bed comprising a traveling main frame, an oscillatory
- 90 95 100 105 110 115 120 125 130

carriage movable upon the main frame in a direction transverse to the path of travel of the main frame, compression rollers carried by said carriage, and means to oscillate the carriage as said carriage approaches the limit of its path of travel in either direction.

5 50. In an apparatus of the character described, means for compacting plastic material deposited upon the road bed, comprising a traveling main frame, a pair of com-

pression rollers movable in a direction transverse to the path of travel of the main frame, and means for alternating the operation of the compression rollers at the limits of their path of travel.
